UNITED STATES PATENT OFFICE.

LOUIS E. GAISSER, OF LOUISVILLE, KENTUCKY, ASSIGNOR TO ALICE E. GAISSER, OF LOUISVILLE, KENTUCKY.

WRENCH.

1,253,227.

Specification of Letters Patent. Patented Jan. 15, 1918.

Application filed October 17, 1916. Serial No. 126,128.

To all whom it may concern:

Be it known that I, LOUIS E. GAISSER, a citizen of the United States, residing at Louisville, in the county of Jefferson and 5 State of Kentucky, have invented a new and useful Wrench, of which the following is a specification.

The device forming the subject matter of this application is a wrench, and one object 10 of the invention is to provide a wrench which may be shifted readily, circumferentially of a nut or the head of a bolt, to permit the wrench to secure a new hold on the nut or the head of the bolt, without removing 15 the wrench.

Another object of the invention is to provide novel means whereby an increased bearing area will be afforded between the actuating lever and the movable jaw, when 20 the lever is moved sidewise to advance the movable jaw toward the fixed jaw.

It is within the province of the disclosure to improve generally and to enhance the utility of devices of that type to which 25 the present invention appertains.

With the above and other objects in view which will appear as the description proceeds, the invention resides in the combination and arrangement of parts and in the 30 details of construction hereinafter described and claimed, it being understood that changes in the precise embodiment of the invention herein disclosed, can be made within the scope of what is claimed, without des- 35 parting from the spirit of the invention.

In the accompanying drawings:

Figure 1 shows in side elevation, a wrench embodying the present invention;

Fig. 2 is a section taken on the line 2—2 40 of Fig. 1;

Fig. 3 is a side elevation wherein parts are broken away;

Fig. 4 is a cross section taken on the line 4—4 of Fig. 2;

Fig. 5 is an end elevation;

Fig. 6 is an elevation showing a modified form of spring adapted to be used in the wrench forming the subject matter of this application.

In carrying out the present invention there is provided a head 1 equipped with a 50 fixed jaw 2. The head 1 has a transverse passage 3 and a longitudinal passage 4 defining side walls 5 and 6, connected by lugs 25. The inner face of the side wall 5 is

equipped with a transverse rib 7. The numeral 8 designates a movable jaw coöperating with the fixed jaw 2, the jaw 8 having a rectangular shank 9 mounted for right line sliding movement in the transverse passage 3. The shank 9 coöperates with the body portion of the movable jaw to form shoulders 10 overhanging the outer end edges of the side walls 5 and 6 of the head 1. In one side of the shank 9 there is fashioned a 60 guide slot 11 receiving the rib 7. In the inner face of the side wall 6 there is formed a transverse recess 12. Located in the recess 12 is a bowed spring 14, the ends of which engage the head portion of the wrench at the 65 ends of the recess 12. The spring 14 bears against the shank 9 of the movable jaw 8 and serves to prevent lost motion between the rib 7 and the guide slot 11. On the inner edge of the shank 9 of the movable 70 jaw 8 there is fashioned a rack, composed of round-ended teeth 15. One side of each tooth 15 is more abruptly inclined, as shown at 20, than is the other side 21, so that the teeth, in effect, point laterally, to a slight 75 extent, as Fig. 3 will show. Connecting the inner edge of the shank 9 of the movable 80 jaw 8 and the outer edge of the shank 9 of the fixed jaw 2 is a longitudinal passage 4, which is a pivot element 16 on which is mounted to 85 swing a lever 17, on the inner end of which is a rack made up of round-ended teeth 18 meshing into the teeth 15 of the movable 90 jaw. Owing to the fact that the sides of the teeth 15 of the movable jaw are differently inclined, as indicated at 20 and at 21, the 95 teeth 18 of the lever 17 will have an increased bearing area on the teeth 15 of the movable jaw when the lever 17 is swung laterally, to move the jaw 8 toward the jaw 2. The side wall 5 of the head 1 at its 100 inner end may be equipped with an outstanding finger piece 23, facilitating a shifting of the head, when the lever 17 is held in the hand of an operator.

The device forming the subject matter of this application is so constructed that, without removing the wrench from a nut or other object which is being turned, the jaws 2 and 8 may be separated, when the lever 17 is swung in one direction, thereby to permit 105 a rotation of the wrench with respect to the nut. On the other hand, when the lever 17 is swung in an opposite direction, the jaws 8 and 2 will grip the nut and effect a rotation thereof.

The lever 17 may be provided with a recess 51. In the recess 51 is located a spring washer 52 which, coacting with the side wall 5, serves to take up lost motion. The 5 spring washer 52 may be replaced by a helical spring 53 shown in Fig. 6.

Having thus described the invention, what is claimed is:—

A wrench comprising a head having a 10 fixed jaw; a movable jaw coöperating with the fixed jaw and including a shank disposed transversely of the head and mounted for right line sliding movement in the head, the shank having a straight rack in its inner 15 edge; and a lever extended longitudinally of the head and pivoted thereto, the lever being provided at one end with a curved

rack composed of round-ended teeth meshing into the teeth of the rack on the movable jaw, the sides of the teeth of the movable jaw being inclined, each of said teeth being more abruptly inclined on one side than on the other, thereby to increase the bearing area between the teeth of the two racks, when the lever is swung laterally to 20 cause the movable jaw to move toward the fixed jaw.

In testimony that I claim the foregoing as my own, I have hereto affixed my signature in the presence of two witnesses.

LOUIS E. GAISSER.
